UNITED STATES PATENT OFFICE.

WALTER RÜEGSEGGER, OF MATZINGEN, SWITZERLAND.

BUNG FOR LIQUID CONTAINERS.

Application filed March 5, 1923. Serial No. 622,930.

To all whom it may concern:

Be it known that I, WALTER RÜEGSEGGER, a citizen of the Republic of Switzerland, residing at Matzingen, in the Canton of 5 Thurgau, Republic of Switzerland, have invented certain new and useful Improvements in and Relating to Bungs for Liquid Containers, of which the following is a specification.

10 Bungs for drawing off and fermenting purposes have already been proposed, in which the air before entering the barrel is subjected to a twofold purification, but cannot be used on account of their projecting 15 parts where the barrels are intended for transport, so that other bungs must be used for this purpose. On the other hand bungs suitable for transport purposes are known. These bungs, however, have the drawback, 20 that they are not constructed so as thoroughly to purify the air as it enters.

The subject of the present invention is a bung for a barrel, which is suitable for transport purposes and enables the air as 25 it enters to be twice purified.

This object is effected according to the present invention by combining with a perforated disc, which is capable of being screwed into the bung sleeve, a cotton wool 30 container, which is provided with packing around its periphery, and by a flange of this container dipping into a liquid container, the communication between which and the cotton wool container and the barrel is capable 35 of being interrupted by screwing down the disc, the liquid container being at the same time pressed on to the packing which makes a tight joint with the barrel.

In the accompanying drawing a constructional example of the subject of the invention is shown in vertical section.

A sleeve 1 with an outwardly turned top flange 2 and an inwardly turned bottom flange 3 is provided with an outside thread 45 4 for the purpose of being driven into the bung hole of a barrel and a short internal thread 5, into which a disc 7 provided with perforations 6 is screwed. Through an axial hole 8 in the disc 7 the hollow stem 9 of a 50 shouldered cup 10 extends. The shoulder 10¹ of this cup is adapted to be pressed on to a packing ring 11 with the object of making a tight joint between the bung and the interior of the barrel. By a nut 13 screwed 55 on the top of the stem 9 the latter 9 is forced to take part in the axial upward movement

of the threaded disc 7. In the hollow stem 9 an excess pressure valve 14 is provided, which under the pressure of a spring 15 closes an opening 16 in the bottom of the 60 cup 10, while on there being an excess pressure in the barrel, it allows the gases to escape. The upper end of the spring 15 abuts against a plug 17 screwed into the 65 stem 9 and having a central bore 18.

The bung has no parts, which project beyond the barrel, and is therefore specially suitable for barrels for transport purposes.

The shouldered cup 10 forms a container for the filtering liquid 19, for instance alcohol. In this liquid a rim 20 is immersed, which extends from a cotton wool container 21 integral with the threaded disc 7 almost to the bottom of the cup 10. In a peripheral groove 22 of the cylindrical cotton wool container 21, there is a packing ring 23, which rests against the inside of the wall of the sleeve 1.

With the parts in the position shown, the shoulder 10¹ of the cup 10 is slightly raised 80 from the packing ring 11 and the air can pass through the cotton wool container 21 and the liquid 19 into the barrel, thus being subjected to a twofold filtration. When the barrel is to be transported, the disc 7 85 and the cotton wool container 21 are slightly screwed down, when the lower surface of the cotton wool container 21 will press on a packing ring 24 lying on a flange 25 of the cup stem 9, the cup 10 thus pressing on the 90 packing ring 11 and pressing the latter on to the flange 3 of the sleeve. This tightly seals the space containing the liquid 19, so that the latter cannot escape from the said 95 space.

What I claim is:—

1. A bung for barrels for transport purposes, comprising a perforated disc capable of being screwed into the bung sleeve, a cotton wool container combined with the said 100 disc and having a peripheral packing and a downwardly projecting rim, a liquid container having a central stem, a face capable of being tightly pressed upon an annular flange of the bung sleeve and a central stem 105 having a flange upon which the bottom of the cotton wool container is capable of being tightly pressed, the said rim of the cotton wool container dipping in the liquid container and the said stem being in lifting 110 connection to the perforated disc.

2. A bung for barrels for transport pur-

poses, comprising a perforated disc capable of being screwed into the bung sleeve, a cotton wool container combined with the said disc and having a peripheral packing and a 5 downwardly projecting rim, a cuplike, centrally bored liquid container having a central hollow stem enclosing a spring, a plug and an excess pressure valve, an annular shoulder capable of being tightly pressed 10 upon an annular flange of the bung sleeve, the said stem having a flange upon which

the bottom of the cotton wool container is capable of being tightly pressed and having also a head resting in a cavity of the said disc and the said rim of the cotton container dipping in the liquid container. 15

In testimony whereof I have affixed my signature in presence of two witnesses.

WALTER RÜEGSEGGER.
